UNITED STATES PATENT OFFICE.

SELDEN I. CLAWSON, OF SALT LAKE CITY, UTAH.

CLOTHESRACK.

Application filed August 22, 1919. Serial No. 319,206.

To all whom it may concern:

Be it known that I, SELDEN I. CLAWSON, a citizen of the United States, residing at Salt Lake City, in the county of Salt Lake 5 and State of Utah, have invented certain new and useful Improvements in Clothesracks; and I do hereby declare the following to be a full, clear, and exact description of the same, reference being had to the accompanying drawings, forming part of this 10 specification.

This invention relates to clothes drying racks of the elevatory type which utilize the heated air and unoccupied space in the upper 15 part of a room for the purpose of drying wet or damp clothes, and has for its object the provision of a portable elevatory rack of such design that the guide rail common to all other elevatory racks known to 20 me may be eliminated and yet the rack be so balanced that the clothes suspended on the arms shall not touch the wall on which the rack is hung.

By making the rack of small capacity, as 25 illustrated herein, it is possible to easily elevate and balance it when loaded with clothes and to make it practicable to operate a number of such small well-balanced racks in succession to distribute the wet laundry 30 evenly about the walls of the room, thus securing the maximum amount of exposed drying surface and also making it possible for the worker to make a cycle of the operation, some of the clothes drying on some of 35 the racks while other racks are being loaded and elevated into position on the rest nails or nails near the ceiling.

In the drawings,—

Figure 1 is a side elevation of the rack 40 in its loaded elevated position, but with the clothes omitted.

Fig. 2 is a front elevation of the wire frame and showing the base block in cross section.

Fig. 3 is a bottom plan view of my device 45 with the wire frame partly broken away for convenience of illustration.

Fig. 4 is a similar view, but showing a modified form of base block and arrangement of the arms.

In the use of the rack of the present invention, it is the intention that the worker shall hang the rack on a nail driven into the wall or other convenient support at such 55 a height as may be desirable for ease of loading the rack with damp clothes on all

of the arms, and shall then elevate the loaded rack by means of the rod which serves the dual function of support during such elevation and of a balancer when in 60 place high on the wall where the unoccupied heated air space near the ceiling is utilized for the drying.

Referring now to the drawings, 5 represents the ceiling of a room of which 6 is the 65 side wall; the latter having driven therein one or more loading nails 7 above which are located a plurality of pairs of co-operating nails 8 and 9, the former, or rest nail, serving to support the loaded rack, while 70 the lower nail 9 tends to prevent side movement of the rack about nail 8 as a pivot.

The rack is composed of three main parts, the wire frame 10, the prop 11 and the base block 12 with its arms 13 which may be integral therewith, but are preferably secured to the lower face of the base block 12 as shown in Figs. 3 and 4. In either of the forms shown the base block is provided with a plane face 14 adapted to lie against the 80 supporting wall 6 and has a notch 15 in each side wall near the face 14 to receive the corner 16 of the wire frame 10. The arms 13 extend either radially as in Fig. 3 which is the preferred form, or parallel to 85 each other as in Fig. 4, and the base block is shaped accordingly.

The wire frame 10 is bent into an open square having in addition to the two corners 16, an upper hook 17 to rest on the nails 7 90 or 8 and the two uneven ends of the wire are twisted together as at 18 to complete the square while the longer end 19 is extended forwardly into a loop 20 which receives the prop 11 which is fastened securely 95 to the base block 12 at 21 in any desired manner, but in such manner that the lower tip 22 of the prop shall rest against the wall 6 when the face 14 is in contact therewith and the wire frame 10 in position upon 100 the proper nail, this being particularly convenient when the rack is upon the loading nail, since at such time the tip 22 rests against the top of the base board (not shown) of the wall 6, and, therefore, assists in supporting as well as balancing the load. Since the frame 10 is formed of a single piece of wire, it may be sprung width-wise to receive the base block 12 by pressing together the hook end 17 and the 110 twisted portion 19.

In operation the racks are hung on the

rest nails near the ceiling when not in use and are taken therefrom one at a time when desired for loading with damp clothes, and placed upon a loading nail 7 with the prop 5 balancing the same, as previously stated. The wet clothes are now placed on the arms of the rack and when properly and evenly loaded the worker takes hold of the prop with both hands and elevates and balances 10 the loaded rack above her head, carries it to the rest nail and, elevating the loaded rack still higher, hangs the rack upon rest nail 8, and then brings the lower triangle of the wire frame into registry with nail 9. An- 15 other rack may now be taken down from the rest nail and hung upon the loading nail. After it has received the load it can be returned to the rest nail and a third rack taken to be loaded.

20 A person can readily see how a number of racks could thus be employed.

The drying of the clothes is greatly accelerated and the work of elevating and balancing the loaded rack is greatly relieved by distributing the laundry in small divisions 25 around the room.

When four racks are in use the first rack loaded will be found dry enough to begin ironing by the time the operator has loaded 30 and hung up the fourth rack load. I consider my invention broad enough to include other designs of construction.

What is claimed is:

1. A drying rack of the character de- 35 scribed, comprising an arm supporting member, a plurality of arms extending in a substantially horizontal direction when the device is in use, hanging means secured to the

supporting member, an extension on said means, and an element secured to said arm 40 supporting member and said extension and frictionally engaging the supporting wall to brace the rack.

2. In a clothes drying rack, a base block having a straight face and a plurality of 45 notches, a flexible wire frame adapted to be sprung to engage said notches and having an extended end bent to form a loop, and a prop passing through said loop and engaging said base block in order to balance the 50 load on said rack.

3. In a clothes drying rack, a base block, a plurality of arms extending therefrom, a wire frame secured to said base block and having an upwardly extending nail-engag- 55 ing member and a downwardly extending prop-engaging member, a prop secured to said base block and to said frame and directed at such angle to said base block and frame that the lower edge of said prop will engage 60 a vertical wall when said frame and base plate are secured thereto.

4. In a clothes rack, means for holding clothes, a wire frame for suspending said means, an angularly extending member on 65 said frame having an eye at the extremity thereof, and an angularly projecting prop secured to said holding means at one end, ex- tending through said eye and frictionally engaging at its lower free end, the support- 70 ing wall.

SELDEN I. CLAWSON.
